UNITED STATES PATENT OFFICE

146,901

DESIGN FOR A BIRDBATH

Ciro Americo Fiorio, Northfield, Ill.

Application December 13, 1945, Serial No. 124,680

Term of patent 7 years

(Cl. D35—3)

To all whom it may concern:

Be it known that I, Ciro Americo Fiorio, a citizen of the United States, residing at Northfield, in the county of Cook and State of Illinois, have invented a new, original, and ornamental Design for a Birdbath, of which the following is a specification, reference being had to the accompanying drawing, forming part thereof.

I claim:

The ornamental design for a birdbath, as shown.

CIRO AMERICO FIORIO.
